MUZZLE RECOIL CHECK FOR FIREARMS

Jacques Emilien Prache, Fontenay sous Bois,
France, assignor to Schneider & Cie, Paris,
France, a special partnership of France

Application May 17, 1948, Serial No. 27,537
In France May 31, 1947

1 Claim. (Cl. 89—14)

1

This invention relates to a muzzle recoil check for firearms, of the type constituted by a pile of removable cup-shaped deflecting members supported by a cylindrical body bored substantially to the diameter of the barrel at the base of the rifling, the said muzzle recoil check comprising openings permitting the gases to escape in order to impinge against the deflectors which deflect them laterally and rearwardly.

In devices comprising piles of deflectors of this nature, it is known to close the lower part of the gaps separating the deflecting elements in order to prevent the gases escaping therefrom from scoring the ground below the gun. Muzzle recoil checks are also known which comprise solely lateral discharge orifices.

The device proposed, which combines these various known methods, has been designed with a view to simplifying the construction while ensuring the possibility of readily replacing the deflecting members, which are exposed to erosion under the effect of the gas jets, and to enable the said device to be adapted with the minimum number of changes to different firing conditions and requirements as to output.

According to the invention, the new muzzle recoil check is constituted by a hollow cylindrical body fitted on the muzzle of the barrel or made in one piece therewith, and provided with two opposite lateral openings of substantially rectangular form which extend over the entire length of the pile of deflecting members which are constituted by oblong plates bored to the external diameter of the aforesaid body, there being formed in each of the said plates two lateral vanes symmetrically disposed to the right and to the left, and the said elements which are fitted over the said body and maintained in the correct position, being locked one against the other and against a shoulder on the body of the device by means of an end nut.

One embodiment of the invention is illustrated, by way of example, in the accompanying drawings, in which:

Figure 1 is a longitudinal view of the device, one half of which is in section and the other half in elevation,

Figure 2 is a plan, one half of which is again a sectional view and the other half an external view,

Figure 3 is a cross section on the line III—III of Figure 2.

In these figures, 1 designates the hollow cylindrical body of the muzzle recoil check secured by screwing on the beaded muzzle portion 2 of

the barrel and bored to a diameter which is at least equal to the diameter of the barrel at the base of the rifling grooves. Formed in the said cylinder 1 are two opposite lateral openings 3 of substantially rectangular form, bounded at the top and bottom by planes extending through the axis.

On the forward part of 1a of the body 1 there is mounted with a sliding fit a pile of deflecting members 4, each of which is constituted by an oblong plate (its larger dimension being in the transverse direction) and naturally has a bore corresponding to the external diameter of the said body. The said plates are positioned and prevented from turning by a longitudinal key 5 secured in a groove 1b in the body 1, while the plates themselves have a similar groove 4a. The various plates in the pile which have parallel faces are locked one against the other and against a shoulder 1c on the body 1 by a nut 6 screwed on the free extremity of the said body with the interposition of an adjusted member 7.

The deflecting plates 4 have laterally hollowed therein concave surfaces 8 and convex surfaces 9 of suitable profile, so as to form guide vanes 10 and the shoulder 1c of the body 1 is similarly shaped at 11, so that the assemblage of plates, when mounted on the cylinder, forms on either side thereof three divergent nozzles through which there flow the gases which have passed through the openings 3, whereby the desired reducing effect is produced on the recoil of the fire-arm.

As will be seen, the pile of plates can be instantly dismounted by simply unscrewing the nut 6.

Of course, the profile of the blades can vary within very wide limits from one vane to the other, and since it is easy to replace one or more of the plates in the same device by plates having vanes of different profile from the vanes of the first plates, this method of construction renders the muzzle recoil check widely adaptable to the firing conditions and to the required output, which is not necessarily the maximum output.

It will be seen that in the embodiment illustrated the angle of deflection from the first nozzle 11—8 is greater than that from the following two nozzles 9—8. However, it may be advantageous to adopt the opposite arrangement in order to prevent deflection of the sheet of gases on to the gun crew, the gas sheets issuing from the downstream nozzles being broken against the

more divergent sheet from the upstream nozzle 11-8.

It is obvious that the device hereinbefore described may be simplified by forming the body 1 by means of a simple extension of the barrel, the said extension having no rifling and comprising lateral openings 3, while a collar fulfilling the function of the shoulder 1c hereinbefore referred to would be provided on the rear part of the said extension.

Having now particularly described and ascertained the nature of my said invention and in what manner the same is to be performed, I declare that what I claim is:

A muzzle recoil check for firearms comprising 15 a hollow cylindrical body adapted to be fitted on the muzzle of a firearm and having two laterally opposed and longitudinally elongated openings for the escape of gases, and means for controlling and deflecting the escaping gases comprising a pile of aligned deflector plates mounted on said body for longitudinal sliding movement, said plates having flat parallel surfaces for engagement with one another to form a solid pile, means for locking said plates in engagement comprising a shoulder on said body at one end of the pile and a nut on said body at the other end of the pile, said plates having projections extending outwardly from both sides of said body, and curved recesses cut into the opposite flat surfaces of each projection between its upper and lower margins to form substantially horizontal rear-

wardly curved vanes extending from said openings to the outer edges of said projections, said projections and vanes forming between them two rows of outwardly extending rearwardly curved nozzles one on each side of said body for deflecting the gases escaping through said openings, the vanes of individual plates having different curved profiles and said plates being interchangeable in the pile for adjustment of the curvature 10 of the nozzles and of the recoil checking effect.
